UNITED STATES PATENT OFFICE.

ELI BROTHERS, OF LYNN, MASSACHUSETTS, ASSIGNOR TO UNITED SHOE MACHINERY COMPANY, OF PATERSON, NEW JERSEY, A CORPORATION OF NEW JERSEY.

LAST.

1,021,821.

Specification of Letters Patent.

Patented Apr. 2, 1912.

Application filed September 23, 1908. Serial No. 454,439.

To all whom it may concern:

Be it known that I, ELI BROTHERS, a citizen of the United States, residing at Lynn, in the county of Essex and Commonwealth 5 of Massachusetts, have invented certain Improvements in Lasts, of which the following description, in connection with the accompanying drawings, is a specification, like reference characters on the drawings 10 indicating like parts in the several figures.

This invention relates to lasts.

The last herein described is designed particularly for use in the manufacture of 15 stitch-down shoes, but the invention may be embodied in lasts employed in making shoes of other kinds.

The invention provides a last designed especially to facilitate the making operations and has particular provision for producing 20 the desired fullness at the toe of the shoe. This last is intended more especially to be used during the operation of lasting and securing the sole to the shoe and it may then be removed from the shoe and be replaced 25 by a last of the usual contour which imparts to the shoe its finished shape. This method of making shoes by the successive employment of two lasts is not herein claimed but is covered by an application 30 filed contemporaneously herewith, Serial No. 454,441.

The invention will be readily understood from the following description, when read 35 in connection with the accompanying drawings, in which,—

Figure 1 is a view in side elevation with a portion in section of a last embodying the present invention, an ordinary last being shown in dotted lines to facilitate comparison; Fig. 2 is a vertical sectional view on the line 2—2 of Fig. 1 showing in dotted lines the corresponding contour of an ordinary last; Fig. 3 is a vertical sectional view on the line 3—3 of Fig. 1, showing in dotted 40 lines the corresponding contour of an ordinary last, and also a stitch-down shoe in position upon the last of Fig. 1; Fig. 4 is a view in vertical section on the line 4—4 of Fig. 1, showing in dotted lines the corresponding contour of an ordinary last; Fig. 5 is a view in plan of the last shown in Fig. 1, and with an ordinary form of last shown 45 in dotted lines.

Referring to the drawings wherein the 50 last shown in full lines represents one em-

bodiment of the invention and the last shown in dotted lines is of a form heretofore used, it will be seen that the two lasts are the same in length and their soles are also equal in width at all points.

From an inspection of Figs. 2, 3 and 4, it will be seen that the last embodying the present invention diminishes in width from the sole upward and in this respect differs from the ordinary form of last. At the toe 60 in the vicinity of line 2—2 of Fig. 1 the present last is of somewhat greater height than the prior last. Furthermore, as is shown in Fig. 2, the ridge which constitutes the high portion of the last at this point, is 65 symmetrically located with reference to the sides of the last so that the sides are free from overhanging portions. The junction of the sole with the sides at the shank has a sharp edge instead of being rounded and, as 70 will appear from Fig. 3, the sides adjacent to the sole constitute gaging abutments against which the upper of the shoe is pressed and which locate in proper position the projecting flanges of the upper. It will 75 be seen from this figure that the diminished width of the last from the sole upward is compensated for by an increase in depth.

The last herein shown comprises a body portion 2 and an instep block 4. The toe tip 80 of the last is provided, with a cavity 6. In lasting the toe portion of a shoe the upper at the toe may be pressed manually by the operator into this cavity and held there while the projecting flange of the upper is 85 being secured to the sole edge. This provides a certain amount of fullness in the upper at the toe which will permit the final shape of the toe to be somewhat more full than would otherwise be the case. The cavity 90 is preferably shallow and of considerable area relatively to its depth. The cavity shown is of greater width and length than depth.

In the preferred mode of use of the last 100 shown as embodying the present invention, the operations of lasting and securing the sole to a shoe are performed while the shoe is mounted upon this last. Thereafter the last may be removed and a last of the form 105 shown in dotted lines upon the drawings may be substituted therefor. This gives to the shoe the ordinary contour which is desired and remains in the shoe during the finishing operations.

Having described my invention, what I claim as new and desire to secure by Letters Patent of the United States is:

A last, having a cavity of greater width and length than depth in the upper side of the toe for the purpose described.

In testimony whereof I have signed my

name to this specification in the presence of two subscribing witnesses.

ELI BROTHERS.
